DISPENSING MACHINE FOR GUM BALLS, CHARMS OR THE LIKE

Sidney Eppy, Forest Hills, N.Y., assignor to Samuel Eppy
& Company, Inc., Jamaica, N.Y., a corporation of
New York

Filed Nov. 12, 1959, Ser. No. 58,317

Term of patent 7 years

(Cl. D52—3)

FIG. 1.

FIG. 2.

FIG. 3.

Fig. 1 is a front view of a dispensing machine for gum balls, charms or the like embodying my new design.

Fig. 2 is a side view thereof.

Fig. 3 is a top view thereof.

The rear and the undisclosed side of the dispenser are substantially the same in appearance as the side shown.

I claim:

The ornamental design for a dispensing machine for gum balls, charm or the like, substantially as shown and described.
